US00D968363S

(12) **United States Design Patent** (10) **Patent No.:** **US D968,363 S**
(45) **Date of Patent:** ** *Nov. 1, 2022

(54) **EARPHONES**

(71) Applicant: **Apple Inc.**, Cupertino, CA (US)

(72) Inventors: **Ryan Ott**, North Hollywood, CA (US); **Carlos M. Santana**, Granada Hills, CA (US); **William R. Rochowicz**, Manhattan Beach, CA (US); **Robert Boyd**, Los Angeles, CA (US); **Martin Gschwandtl**, San Francisco, CA (US); **Guillaume Raoult**, San Francisco, CA (US); **Christopher Kuh**, San Francisco, CA (US); **Robert Brunner**, Glen Ellen, CA (US)

(73) Assignee: **Apple Inc.**, Cupertino, CA (US)

(*) Notice: This patent is subject to a terminal disclaimer.

(**) Term: **15 Years**

(21) Appl. No.: **29/814,679**

(22) Filed: **Nov. 8, 2021**

Related U.S. Application Data

(63) Continuation of application No. 29/783,996, filed on May 17, 2021, now Pat. No. Des. 935,436, which is a continuation of application No. 29/717,269, filed on Dec. 16, 2019, now Pat. No. Des. 919,595, and a continuation of application No. 29/717,267, filed on Dec. 16, 2019, now Pat. No. Des. 919,594, which is a continuation of application No. 29/685,000, filed on Mar. 25, 2019, now Pat. No. Des. 896,200.

(57) **CLAIM**

The ornamental design for earphones, as shown and described.

DESCRIPTION

FIG. 1 is a top front perspective view of earphones showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dashed broken lines in the figures show portions of the earphones that form no part of the claimed design.

1 Claim, 6 Drawing Sheets
